Primary Examiner — W. A. Teddy Falloway(74) *Attorney, Agent, or Firm* — Kerrick Bachert, PSC;
Laura M. Hagan(57) **CLAIM**

The ornamental design for the combination frame and shelf, as shown and described.

DESCRIPTION

FIG. 1 is a front perspective view of the combination frame and shelf with the shelf in an open position;

FIG. 2 is a top plan view of the combination frame and shelf;

FIG. 3 is bottom plan view of the combination frame and shelf;

FIG. 4 is left side elevation view of the combination frame and shelf; the right side being a mirror image thereof;

FIG. 5 is a front elevation view of the combination frame and shelf;

FIG. 6 is a back elevation view of the combination frame and shelf; and,

FIG. 7 is another front perspective view of the combination frame and shelf, with the shelf in a closed position.

The broken lines illustrate portions of the Combination Frame and Shelf that form no part of the claimed design.
